United States Patent Office

Des. 218,161
Patented July 28, 1970

218,161

TRANSOM PLATFORM OR SIMILAR ARTICLE

Richard J. Kadison, Box 3, West Pittston, Pa. 18643

Filed Dec. 26, 1968, Ser. No. 15,116

Term of patent 14 years

Int. Cl. D6—99

U.S. Cl. D15—8

FIG. 1

FIG. 2

FIG. 3

FIG. 1 is a top perspective view of a transom platform embodying my new design.

FIG. 2 is a side elevational view thereof; and

FIG. 3 is a front view thereof, in an alternate position.

I claim:

The ornamental design for a transom platform or similar article, substantially as shown.
